ATMOSPHERE HEAT-TREATING FURNACE

Albert Krauscope, Jeannette, and Gerhard P. Lessmann, Forest Hills, Pa., assignors to Westinghouse Electric & Manufacturing Company, East Pittsburgh, Pa., a corporation of Pennsylvania

Application June 7, 1941, Serial No. 396,996

3 Claims. (Cl. 20—68)

Our invention relates generally to heat-treating furnaces of a type having a heating-chamber in which a charge is heat-treated while surrounded by a desired atmosphere, and more particularly relates to a heat-treating furnace having a bottom charging-opening closed by a suitable bottom closure or door, and provided with a gas-sealing means for limiting leakage of atmosphere or air around the edges of the closure in the closing position thereof.

It is an object of our invention to provide a heat-treating furnace having a bottom charging-opening, through which a charge is either raised or lowered, or both, the charging-opening being provided with a closure means provided with a gas-sealing member-means adapted to contact the wall-structure of the heating-chamber to provide a gas-sealing between the closure and the wall-structure.

It is an object of our invention to provide a gas-sealing means for a furnace of the type described, which sealing means is automatically operable to effect its sealing function when the closure seats in the charging-opening of the furnace.

It is a further object of our invention to provide a gas-sealing means for a furnace of the type described, in which the wall-structure of the furnace is provided with a gas-sealing contact member-means engageable by a gas-sealing closure member-means on the closure when the closure is moved to closing position, the closure member-means being disengageable from the gas-sealing contact member-means when the closure is moved from closing position.

In accordance with our invention, the closure is provided with a U-shaped trough-member near its edges. A structure, including compressible material, is slidable in this trough-member, and pressed upwardly therein by spaced compression springs, with the movement of the structure however being limited. When the closure engages a suitable cooperating gas-sealing member-means on the wall-structure of the furnace about the charging-opening, the spring-pressed structure engages the co-operating gas-sealing contact member-means of the wall-structure, and abuts it, being depressed downwardly against the action of its compression springs by the upward motion of the closure moving to final closing position, thus providing the gas-sealing means for limiting gas-leakage around the edges of the closure.

Many novel features, and advantages, innovations and objects of our invention, in addition to

those mentioned above, will be apparent from the following description thereof which is to be taken in connection with the accompanying drawings, on varying scales, in which:

5 Figure 1 is a transverse sectional view showing, somewhat diagrammatically, a furnace embodying our invention.

Fig. 2 is a vertical sectional view through the spring-pressed structure of the closure member-means of the gas-sealing means,

Fig. 3 is a fragmentary elevational view of the closure member-means of the gas-sealing means, which is at one corner of the closure,

Fig. 4 is a fragmentary plan view of the closure member-means of the gas-sealing means,

Fig. 5 is an elevational view of a contact element of the closure member-means of the gas-sealing means, which contact element is a metallic sheet. It is shown as it appears in one stage of its manufacture,

Fig. 6 is an elevational view of a bar used as part of the closure member-means of the gas-sealing means,

Fig. 7 is a cross-sectional view of a modified form of closure member-means for a gas-sealing means in accordance with our invention, and

Fig. 8 is a plan view, similar to Fig. 5, of a contact element of the modified closure member-means.

30 Referring more particularly to Fig. 1, a heat-treating furnace is shown, comprising a wall-structure 1 comprising four vertical walls 2 covered by a top wall 4, the vertical walls and top wall defining a heating-chamber 6 adapted to heat-treat a charge while enveloped by any suitable controlled or other desired atmosphere. The wall-structure 1 is suitably encased in an outer metallic shell 8.

The furnace may be constructed in the manner shown and claimed in the copending application of Elmer K. Hansen, Serial No. 397,007, filed concurrently herewith, and assigned to the assignee of this application.

40 The furnace 1 is provided with a bottom charging-opening 10 through which a charge is adapted to be raised or lowered, or both, the charge being adapted to rest on a closure indicated in its entirety by the reference numeral 12.

A closure of the type shown in more particularly described and claimed in the application of G. P. Lessmann, Serial No. 396,997, filed concurrently herewith and assigned to the assignee of this application. The closure 12, briefly, comprises a gas-impervious bottom or base plate 14 supporting a refractory hearth 16 which is shaped

to conform to the charging-openings 10, but is slightly smaller. A gas-sealing means, indicated in its entirety by the reference numeral 18, is provided near the edges of the base plate 14 and is around the hearth 16.

The closure 12 further comprises a suitable understructure for rotatably supporting a pair of spaced front wheels 20 and spaced rear wheels 22, the front wheels riding on a pair of rails such as the rail 24 and the rear wheels riding on a pair of rails such as the rail 26, the wheels 20 and 22 being somewhat axially displaced, or transversely spaced with respect to the direction of movement of the closure. The rails 24 and 26 are curved upwardly, as shown, so that the closure can be moved to closing position by upward motion while maintained substantially horizontal. The closure is operated by a suitable moving means comprising a pair of cylinders 28 at the forward corners of the closure, the cylinders having suitable pistons and piston rods pivotally connected to the clevises 30 at the corners of the closure. The cylinders are also pivotally supported, as at 32, to accommodate the travel of the closure in its combined horizontal and vertical movements.

The rails 24 and 26 are provided with a horizontal portion 34 upon which the closure 12 rests in uncovering position. The curvature of the rails is such that when the closure is moved from its extreme open position on the horizontal portion 34 of the rails 24 and 26, to closing position, it rides upwardly with gradually increasing vertical directional components so that the hearth 16 suitably seats in the charging-opening 10, and so that the gas-sealing means 18 is made effective.

In accordance with our invention, the gas-sealing means 18 comprises a stationary contact member-means 36 at the bottom of the vertical walls 2, the contact member-means being gas-tightly secured to the outer shell 8. The contact member-means preferably is a frame-like plate whose edges can be welded to, or made integral with, the shell 8, and which is completely around the wall-structure 1. The gas-sealing means 18 further comprises a closure member-means 38 on the closure 12, capable of cooperating with the contact member-means 36 by contact or abutting engagement.

The closure member-means 38 comprises a trough-member 39 around the hearth 16, following the edges of the base plate 14, this trough-member 39 comprising an inner upstanding frame-like leg 40 gas-tightly secured to the base plate 14, and an outer upstanding frame-like leg 42 also gas-tightly secured to the base plate 14 in spaced relation to the leg 40. The legs 40 and 42 are preferably of metal. The closure member-means 38 also comprises a plurality of spaced springs 44 in the trough-member 39, the springs 44 being vertically disposed on upstanding spaced short tubes 46 secured to the base plate 14, the springs pressing upwardly on a bar 48 also provided with spaced short depending tubes 50 which are inside the springs 44 and aligned with the short tubes 46. A plurality of bars 48 are arranged end-to-end in the trough-member 39.

The closure member-means 38 further comprises a plurality of contact-sheets 52, each of which is bent in the form of an inverted U, each contact-sheet having a top portion 54 and depending legs 56 and 58, the legs being slidable in the trough-member 39 of the closure member-means, the leg 58 sliding on the side of the leg 42 of the trough, and the leg 56 sliding on the side of the leg 40 of the trough. Compressible mate-

rial 60, which preferably comprises a plurality of sheets of a compressible substance, such as asbestos gasketing, or other heat-resistant and heat-insulating sheet-material, is placed between the top portion 54 of the contact-sheets 52 and the bars 48, the bars being narrower than the U of the contact-sheets 52.

The springs 44 are compression springs so that they normally tend to force a bar 48, the compressible material 60 thereon, and an associated U-shaped contact sheet 52 upwardly, this motion, however, being limited by providing a cut-out groove or hole 62 in a leg, shown as the leg 58 of the U-shaped contact-sheet 52, in which hole or groove 62 the stem of a screw 64 extends, the screw being threaded in any suitable threaded hole in a leg 42 of the closure member-means 38, a plurality of grooves 62 and screws 64 being spaced along the gas-sealing means.

The closure member-means 38 of the gas-sealing means 18 follows the edges of the base plate 14 and a corner of the arrangement is shown in Fig. 4, in which two right-angular U-shaped contact-sheets 52 abut each other, and similar abutting joints are provided between the upstanding legs 40 and between the upstanding legs 42 of the trough-member 39 of the closure member-means 38.

Fig. 5 shows a contact-sheet 52, this sheet being provided with a plurality of spaced V-shaped cut-outs 70 along the legs 50, and 72 along the leg 56. In assembling the contact-sheet, the legs 56 and 58 are bent over to provide the proper top portion 54, which is solid and flat. The V cut-outs 70 and 72 are provided to permit a certain degree of lengthwise flexibility in the U-shaped contact-sheet 52 and thereby assure a good contact between the contact member-means 36 of the wall-structure and the top portion 54 of closure member-means.

In operation, and assuming the closure in open position, the springs 44 move the U-shaped contact-sheet or -sheets 52 upwardly as far as the screws 64 permit, and when the closure is moved to closing position, the tops 54 will engage the frame-like contact member-means 36. As the closure is forcibly moved into final closing position by the pneumatic cylinder 28, the springs 44 are compressed, and the legs 40 and 42 of the trough-member 39 slide upwardly with respect to the legs 56 and 58 of the U-shaped contact-sheets 52, thereby compressing the compressible material 60 between the bars 48 and the top portions 54 which no longer can move upwardly because of their engagement with the frame-like contact member-means 36 of the wall-structure 1. Compression of the material 60 closes the open portions of the cut-outs 70 and 72. The stack of asbestos strips 60 constitutes a substantially gas-tight sealing-means which protrudes from the trough 39 and engages the bottom sealing-edge 36 of the furnace. Excessive wear at the contact-surface of the asbestos is prevented by the metal surface-lining 54 thereon. The flexibility of the asbestos sheet-material enables it to close the gaps which would otherwise be formed by the inevitable warping of the door or closure-member, due to the excessive heat of the furnace, and at the same time the asbestos itself is able to withstand the heat and to provide heat-insulation for shielding the springs 44 from the furnace-heat. The metal contact-strip 54 of the asbestos air-sealing means is itself kept flexible by having its asbestos-engaging side-portions 56 in the form of a plurality of discrete

prongs 56, instead of using a continuous sheet-metal channel, which would be more rigid.

The springs 44, back of the asbestos sealing-strips 60, provide the necessary elasticity of the sealing-surface. The pressure of the springs 44 further forces the top portions 52 of the U-shaped contact sheets 52 snugly against the contact member-means 36. When the closure is moved to open position, the closure member-means 38 ultimately disengages the contact member-means 36 in an obvious manner. It is, of course, highly desirable to move the closure upwardly to closing position when the two member-means of the gas-sealing means 18 engage. However, slight horizontal movement is also tolerable because the top portions 54 of the U-shaped contact-sheets 52 can slide on the frame-like plate contact member-means 36.

Figs. 7 and 8 show a modified form of closure member-means which is adapted to cooperate with a contact member-means on the bottom of the wall-structure 1 which is in the form of a depending narrow frame. In this figure a U-shaped trough-member 80 having small upper inturned flanges 82 is provided for receiving a plurality of compression springs 84 which press against one or more bars 86. Above the bars 86 is placed compressible material 88 which is topped by metallic contact-sheet or -sheets 90 having down-turned lugs 92, slideable on the sides of the trough-member, and a top portion 94 which engages a frame-like contact member-means 96 gas-tightly secured under the wall-structure 1, to the outer shell 8. The flanges 82 limit upward action of the springs 84.

In the operation of this modification, upward movement of the trough 80, when the closure 12 is seating in the charging-opening 10, will cause engagement of the top portion 94 of the closure member-means with the stationary contact member-means 96 depending from the wall-structure 1. This contact engagement between the top portion 94 and the contact member-means 96 takes place, as in the prior modification, before the closure is fully seated in the charging opening in proper closing position. As the closure moves upwardly to full closing position, the compressible material 88 is compressed snugly against the side walls of the trough 80.

While we have shown our invention in forms which we now believe to be preferred embodiments thereof, it is obvious that many changes

may be made and equivalents substituted in the particular constructions shown.

We claim as our invention:

1. A sealing means adapted to bar the leakage of gas through the joint between a furnace-door and the door-seat of a furnace, comprising a heat-resistant elongated trough-member; a compressible and flexible stack of heat-resistant and heat-insulating material restrictably movable in said trough-member; means comprising a plurality of spaced spring-means between the bottom of said trough-member and said stack for pressing said stack outwardly at a plurality of points; and a flexible sheet-metal means comprising discrete side-prongs for engaging the sides of said stack and of said trough-member and comprising a contact-portion on the outer side of said stack between the said sides thereof; said stack being of such height as to extend beyond side-edges of said trough-member and to seal the spaces between said side-prongs in sealing positions of said sealing means.
2. A sealing means adapted to bar the leakage of gas through the joint between a furnace-door and the door-seat of a furnace, comprising a heat-resistant elongated trough-member; a compressible and flexible stack of heat-resistant and heat-insulating material restrictably movable in said trough-member; a flexible sheet-metal means having discrete side prongs engaging the sides of said stack and slidably engaging the sides of said trough-member, said sheet-metal means further comprising a contact-portion from which said side-prongs extend, said contact-portion being on the outer side of said stack between the said sides thereof; and means for exerting pressure on said stack along the length of said trough-member for compressing said stack in sealing positions of said sealing means; the height of said stack being such as to extend beyond the side-edges of said trough member and to seal the spaces between said slide-prongs in such sealing positions of said sealing means.
3. The invention of claim 1 characterized by said contact-portion of said sheet-metal means comprising a substantially solid, flat and elongated metal-member, the side-prongs extending sufficiently close to said elongated metal-member to permit lengthwise deformation thereof.

ALBERT KRAUSCOPE,
GERHARD P. LESSMANN.
